CUP RACK

John Clark Brown, Upper Montclair, N. J.

Application November 27, 1953, Serial No. 27,809

Term of patent 14 years

(Cl. D33—3)

Fig. 1.

Fig. 2.

To all whom it may concern:

Be it known that I, John Clark Brown, have invented a new, original, and ornamental Design for Cup Racks, of which the following is a specification, reference being had to the accompanying drawing, forming part thereof.

Figure 1 is an isometric view of the cup rack; and Figure 2 is an end view thereof.

I claim:

The ornamental design for a cup rack, substantially as shown.
